UNITED STATES PATENT OFFICE.

JAMES HENRY GIBSON, OF BROOKLYN, NEW YORK.

HAT HOLDER.

Application filed June 24, 1926. Serial No. 118,399.

This invention relates to a hat holder adapted to be attached to a suitable support with which it combines to releasably hold a hat.

5 The principal object is a hat holder of extremely simple construction, inexpensive to produce, and capable of application to a suitable support, such as the side door of an automobile, the back of the front seat 10 thereof, or on the backs of theater chairs, or on any available support suitable for the intended purposes.

With the foregoing, other objects of the invention will appear from the embodiment 15 of the invention which by way of example is described in the following specification and illustrated in the accompanying drawings, in which—

Figure 1 is a view illustrating the hat 20 holder of the present invention in use.

Fig. 2 is a sectional view on the line 2—2 of Fig. 1.

Fig. 3 is a sectional view on the line 3—3 of Fig. 1.

25 The hat holder consists of a device 10, and attaching means 11 for effecting the attachment of the device 10. In the present embodiment, the device 10, and all but the securing elements of the attaching means 11 are produced from two pieces of material, 30 one piece being in the form of an elastic strip, and the other piece of an inelastic cord or the like. The opposite ends of the inelastic cord are attached to the elastic strip.

35 Under this arrangement the device 10 will consist of an elastic hat crown engaging section 12 and an inelastic hat crown engaging section 13. The opposite ends of the section 13 may be secured in any suitable manner, and in the present instance are attached 40 in loops 14 formed in the strip of elastic material to respectively receive the ends of the section 13, the said ends then being sewed to the loops.

45 The attaching means 11 will include the elastic sections 15 beyond the loops 14, which, it will be observed are at opposite ends respectively of the device 10. Suitable fastening elements 16 are provided for securing 50 the ends of the elastic sections 15 to any suitable support such as the one designated 17 in the drawing, which represents the inside of a door of an automobile.

The inelastic section 13 of the device 10 55 is longer than the elastic section 12 in its normal condition, or in other words, before

it is stretched. A hat is held in place by engaging the sections 12 and 13 with the crown thereof so that the inelastic section 13 will embrace any part of the side portion of the crown as at 18, and the elastic section 12 will be disposed over the top of the crown as indicated at 19. In this way a hat will be effectively and releasably retained in place. If desired the section 12 60 may be made to embrace the side of the crown of the hat opposite to that embraced or engaged by the section 13. By providing the elastic sections 15, greater facility is had in the hat holding and hat removing 65 operations.

I claim:

1. A hat holder comprising a device engageable with the crown of a hat to hold the hat in place, said device consisting of 75 an elastic crown engaging section, and an inelastic crown engaging section, said inelastic crown engaging section connected to said elastic crown engaging section; and attaching means for effecting the attachment 80 of said device.

2. A hat holder comprising a device engageable with the crown of a hat to hold the hat in place, said device consisting of 85 an elastic crown engaging section, and an inelastic crown engaging section, said inelastic crown engaging section being longer than the elastic crown engaging section when the latter is in its normal condition; and attaching means for effecting the attachment 90 of said device.

3. A hat holder comprising a device engageable with the crown of a hat to hold the hat in place, said device consisting of 95 an elastic crown engaging section, and an inelastic crown engaging section; and attaching means for effecting the attachment of said device, said attaching means including elastic members, there being one elastic member connected to each side of said device. 100

4. A hat holder comprising a device engageable with the crown of a hat to hold the hat in place, said device consisting of an elastic crown engaging section, and an inelastic crown engaging section; and attaching means for effecting the attachment of 105 said device, said attaching means including elastic members, there being one elastic member connected to each end of said elastic 110 crown engaging section.

5. The combination with a support, of a

hat holder comprising an elastic strip, means attaching each end of said elastic strip to said support, said elastic strip disposed contiguous said support, and an inelastic member having the opposite ends thereof secured to said elastic strip.

6. The combination with a support, of a

hat holder comprising an elastic strip, means attaching each end of said elastic strip to said support, said elastic strip disposed contiguous said support, and a flexible inelastic member having the opposite ends thereof secured to said elastic strip.

JAMES HENRY GIBSON.
